(57) **CLAIM**

The ornamental design for a crafting tool, as shown and described.

DESCRIPTION

FIG. 1 is a front right bottom perspective view of one embodiment of a crafting tool in accordance with the present invention.

FIG. 2 is a back right bottom perspective view showing the crafting tool of FIG. 1.

FIG. 3 is a front elevation view showing the crafting tool of FIG. 1.

FIG. 4 is a left elevation view showing the crafting tool of FIG. 1.

FIG. 5 is a right elevation view showing the crafting tool of FIG. 1.

FIG. 6 is a top plan view showing the crafting tool of FIG. 1.

FIG. 7 is a bottom plan view showing the crafting tool of FIG. 1.

FIG. 8 is a rear perspective view showing the crafting tool of FIG. 1.

FIG. 9 is a front right bottom perspective view of another embodiment of a crafting tool in accordance with the present invention.

FIG. 10 is a back right bottom perspective view showing the crafting tool of FIG. 9.

FIG. 11 is a front elevation view showing the crafting tool of FIG. 9.

FIG. 12 is a left elevation view showing the crafting tool of FIG. 9.

FIG. 13 is a right elevation view showing the crafting tool of FIG. 9.

FIG. 14 is a top plan view showing the crafting tool of FIG. 9.

FIG. 15 is a bottom plan view showing the crafting tool of FIG. 9.

FIG. 16 is a rear perspective view showing the crafting tool of FIG. 9.

FIG. 17 is a front right bottom perspective view of another embodiment of a crafting tool in accordance with the present invention.

FIG. 18 is a back right bottom perspective view showing the crafting tool of FIG. 17.

FIG. 19 is a front elevation view showing the crafting tool of FIG. 17.

FIG. 20 is a left elevation view showing the crafting tool of FIG. 17.

FIG. 21 is a right elevation view showing the crafting tool of FIG. 17.

(Continued)

FIG. 22 is a top plan view showing the crafting tool of FIG. 17.

FIG. 23 is a bottom plan view showing the crafting tool of FIG. 17.

FIG. 24 is a rear perspective view showing the crafting tool of FIG. 17.

FIG. 25 is a front right bottom perspective view of another embodiment of a crafting tool in accordance with the present invention.

FIG. 26 is a back right bottom perspective view showing the crafting tool of FIG. 25.

FIG. 27 is a front elevation view showing the crafting tool of FIG. 25.

FIG. 28 is a left elevation view showing the crafting tool of FIG. 25.

FIG. 29 is a right elevation view showing the crafting tool of FIG. 25.

FIG. 30 is a top plan view showing the crafting tool of FIG. 25.

FIG. 31 is a bottom plan view showing the crafting tool of FIG. 25.

FIG. 32 is a rear perspective view showing the crafting tool of FIG. 25.

FIG. 33 is a front right bottom perspective view of another embodiment of a crafting tool in accordance with the present invention.

FIG. 34 is a back right bottom perspective view showing the crafting tool of FIG. 33.

FIG. 35 is a front elevation view showing the crafting tool of FIG. 33.

FIG. 36 is a left elevation view showing the crafting tool of FIG. 33.

FIG. 37 is a right elevation view showing the crafting tool of FIG. 33.

FIG. 38 is a top plan view showing the crafting tool of FIG. 33.

FIG. 39 is a bottom plan view showing the crafting tool of FIG. 33.

FIG. 40 is a rear perspective view showing the crafting tool of FIG. 33.

FIG. 41 is a front right bottom perspective view of another embodiment of a crafting tool in accordance with the present invention.

FIG. 42 is a back right bottom perspective view showing the crafting tool of FIG. 41.

FIG. 43 is a front elevation view showing the crafting tool of FIG. 41.

FIG. 44 is a left elevation view showing the crafting tool of FIG. 41.

FIG. 45 is a right elevation view showing the crafting tool of FIG. 41.

FIG. 46 is a top plan view showing the crafting tool of FIG. 41.

FIG. 47 is a bottom plan view showing the crafting tool of FIG. 41.

FIG. 48 is a rear perspective view showing the crafting tool of FIG. 41.

FIG. 49 is a front right bottom perspective view of another embodiment of a crafting tool in accordance with the present invention.

FIG. 50 is a back right bottom perspective view showing the crafting tool of FIG. 49.

FIG. 51 is a front elevation view showing the crafting tool of FIG. 49.

FIG. 52 is a left elevation view showing the crafting tool of FIG. 49.

FIG. 53 is a right elevation view showing the crafting tool of FIG. 49.

FIG. 54 is a top plan view showing the crafting tool of FIG. 49.

FIG. 55 is a bottom plan view showing the crafting tool of FIG. 49; and,

FIG. 56 is a rear perspective view showing the crafting tool of FIG. 49.
